UNITED STATES PATENT OFFICE.

WILLIAM H. EMOND, OF SYRACUSE, NEW YORK.

DOOR CONSTRUCTION FOR VEHICLES.

Application filed September 13, 1923. Serial No. 662,472.

This invention relates to vehicles and more particularly to the construction of bodies for automotive vehicles of the closed type and a particular purpose is to provide 5 a type of door which by virtue of a novel method of construction made practicable thereby not only will offer advantages in use as a completed article but which may be more rapidly, conveniently and cheaply constructed, assembled and installed than doors 10 as at present known.

My invention will be more fully understood by reference to the following description taken in connection with the accompanying drawings, wherein for the purposes of illustration I have shown a vehicle and a door therefor which by its construction and method of building serves as an illustrative embodiment of my invention. In my patent 15 1,570,560, granted Jan. 19, 1926 on an application constituting a division of the present application I have claimed the construction of the body and herein claim the door as such.

20 In the drawings,

Fig. 1 is a partial side elevation of the body of a closed vehicle;

Figs. 2 and 3 are sections on an enlarged scale on the lines 2—2 and 3—3 of Fig. 1, 25 respectively;

Fig. 4 is an elevation of one of the units of which the door is constructed as seen from the inner side of the door;

Fig. 5 is a section on the line 5—5 of 30 Fig. 4;

Fig. 6 is an elevation of a cooperating unit from which the door is constructed;

Figs. 7 and 8 are sections on the lines 7—7 and 8—8 of Fig. 6, respectively;

Fig. 9 is an elevation of the door substantially complete on a somewhat larger scale; and

Fig. 10 is a section on the line 10—10 of Fig. 9.

45 My invention finds particular application to that type of door wherein the upper portion accommodates a window, usually arranged to slide vertically. This type of door is common in automotive vehicles of the closed type. Such doors considered as a whole are of relatively complicated construction and are large and unwieldy. In accordance with the method which constitutes a part of my invention in one aspect thereof and which may be utilized in constructing 50 the embodiment thereof herein disclosed I

construct the door of a plurality of units, each of which is relatively easy to handle and which may be built and completed if desired by a series of jig operations at a bench 60 and which then may be assembled by an exceedingly simple operation to provide the complete door structure. In the form of the invention illustrated as an example, the construction of door adapting itself to this 65 method of construction possesses as a completed article and as a portion of the vehicle to which it is applied important advantages as will appear as the detailed description proceeds.

70 Referring to the drawings, in Fig. 1 I have shown a portion of a closed automobile body comprising a lower body section 11 from which the top 13 is supported by front 75 posts 15 and side posts 17. The body section 11 is provided with door openings and certain of the posts, as, in the case of the forward door, the posts 15 and 17 at the left of Fig. 1, rise at the side of these openings defining door frames extending from the floor to the roof or top. The door received by this frame comprises a lower door section proper 19 closing the opening in the lower body section 11 and an upper portion 21 in the nature of a window received between the top-supporting posts which define 80 the sides of the door opening.

85 Referring to Figs. 2 and 3, while the construction of the door frame might be of any desired or suitable type, conveniently the 90 posts 15 and 17 are of suitable tubular steel shapes and the side posts 17, as illustrated by Figs. 2 and 3, may be of counterpart form, although reversed in position in the example illustrated to accommodate the 95 front window 21 and second window 21^a and to provide between them for an intermediate section of panelling or glazing 23. A further description of the vehicle as such is herein postponed to a detailed description of 100 the door alone.

105 The door herein illustrated may be constructed in two relatively light and wieldy units and in the form shown one of these units, illustrated particularly in Fig. 4, provides for the assembly and coordination of the parts relating to the window or glazing which forms the upper part of the complete door and the other unit illustrated in Fig. 6 might be said in a general way to comprise 110 the lower door portion 19. For convenience in referring to these units and without any

defining intention I shall herein call them the window unit and the door unit.

Referring to Figs. 4 and 5, the window unit may comprise a suitable tall window frame, 5 preferably constructed of metal, and embodying the two channel sides 25 more clearly illustrated in Fig. 2 which provide guideways in which the light or glazing of the window, whether or no equipped with a sash, may 10 slide. In the form of the invention illustrated the glass is fitted directly into these channels without any sash but with the customary felt packing 26 and in this instance the side members preferably have the sectional form clearly illustrated in Fig. 2 15 with a tubular body portion. The window frame is completed by lower and upper cross members 27 and 29 and the member 29 is secured to the members 25 by the angles 31 and is conveniently made readily removable as indicated in Fig. 4 to provide 20 access to the interior of the channels so that the light or pane of the window may be readily slid into the channels from the top either before or after the window section 25 now being described is assembled with the door section. Secured to the side members 25 (see Fig. 5), conveniently by means of 25 angles 33, is the metallic lock-bar 35 suitably formed to accommodate the lock and in cooperation with the rectangular window frame providing for the support of various parts and mechanisms which are associated 30 with or used in controlling the window. As a graphic example I have herein partially 35 illustrated a suitable window regulator 37, so-called, for raising and lowering the window in the frame and which is supported on the lower cross member 27 and the lock-bar 40 35. It will be seen that while the unit shown in Fig. 4 is relatively large, it is of light and simple construction and it may be readily handled and prior to any assembly 45 with the other parts of the door, the various mechanisms associated with the sliding window proper may be secured in position and adjusted.

Referring now to Figs. 6, 7 and 8, the lower door section is constructed as an independent 50 unit and may comprise a lock pillar 39, a hinge pillar 41 and a bottom rail 43, these parts being conveniently, though not necessarily, constructed of wood, a belt-bar 45 joining the upper ends of the pillars and the 55 outer panel 47. These parts, though relatively bulky and heavy constitute a unit relatively small in size and correspondingly wieldy. The inner faces of the pillars 39 and 41 are provided with the grooves or 60 sockets 49 adapted to receive the lower portion of the window frame and the upper portions and one flange of these sockets is cut away providing the rabbets 51 against which portions of the channels 25 of the window unit fit and also receiving the lock-bar 35

of the window unit. This door unit may be handled by jig operations on the bench, constructed as shown and completed with any necessary or usual fittings. The two units as shown in Figs. 4 and 6 may then 70 be assembled to form the substantially complete door as shown in Figs. 9 and 10 by simply inserting the lower portion of the window frame into the open tops of the sockets 49 and securing the belt-bar 35 to the pillars, either before or after the lower door section 19 is hung and either before or after 75 the window pane or light proper is inserted through the upper ends of the channels. In either instance all the necessary parts and mechanisms for controlling and operating the window may be attached, lined up and adjusted on the window frame unit as shown in Fig. 4 before it is assembled with the door section of Fig. 6 and likewise the door section may be completed and provided with suitable or desired fittings before it is assembled with the large window casing. At the same time the bringing together or assembling 80 of these two units is substantially a mere juxtaposition or fitting together instead of a building operation.

I have not attempted to show in detail, particularly in Figs. 4 and 6, all the various elements or fittings which might be attached or adjusted to the window unit or the door unit in the course of their construction as the number and nature of these might vary in accordance with circumstances and the dictates of convenience. The illustrations in Figs. 4 and 6 and to an extent 95 the illustrations in Figs. 9 and 10 may be taken, therefore, as somewhat diagrammatic graphical illustrations from which the principles of the invention will be readily understood in view of this statement. It will also be understood that the interior surface of the lower portion of the door illustrated in Figs. 9 and 10 is upholstered or 100 finished in any suitable or desired way.

Referring to Fig. 10, the door may be completed by the removable sills 53 and 55 fitting the sides of the window and its frame and closing the top of the door section. Conveniently, both the sills are removable or displaceable, and in particular the sill 55 to permit the light proper to be inserted into the upper end of the channels 25 when the top piece or lintel 29 is removed in the manner illustrated in Fig. 4 and to permit 115 any fitting or framing at the bottom of the light to pass into the interior of the door structure, for instance, for connection to the window controlling mechanism 37.

In the preferred embodiment of the invention shown the pillars 39 and 41 extend only substantially half the height of the door and the upper section which extends above the lower body section 11 of the vehicle illustrated in Fig. 1 consists solely of 120 125 130

the relatively light window frame having the side channel section 25 and this frame is adapted to close as indicated in Fig. 2 into the rabbets of the top-supporting posts 5 to close the upper portion of the door opening which is defined by these posts and to complete the enclosure of the vehicle. Such a construction is particularly desirable in that merely the narrow and inconspicuous 10 metallic window frame is exposed above the lower body section of the vehicle providing a neater and more attractive finish and permitting a maximum area of the sides of the vehicle to be of glass construction with relatively 15 small structural frames or posts to obstruct the vision of occupants. At the same time this window frame as illustrated in Fig. 4 is of a substantial rigid construction and facilitates the ready installation of 20 the window proper as contrasted with the difficult task of attaching guides to the sides of an assembled door and the accurate fitting and alignment of such guides.

Referring to Figs. 9 and 1, it will be seen 25 that the window frame section 25 is of less width than the door section 19. This permits the posts 15 and 17 to be offset inwardly from the corresponding jambs beneath them. In particular, the forward 30 posts 15 which rise adjacent the cowl of the vehicle are offset rearwardly and the opening between them brought closer to the driver's seat. Consequently the angle of vision through the windshield opening is 35 increased and at the same time the elimination of the customary heavy frame-work forming a continuation upwardly of the pillars of the door provides for a minimum obstruction to the view and the same is true 40 of the other parts of the vehicle. The post 17, and the channel 25 which fits thereagainst, need occupy no more space than the upper portion of the corresponding pillar or side frame member of a conventional 45 door, even disregarding the post or jamb with which such a pillar cooperates.

In the preferred form of the invention here shown it might be said that the skeleton unit shown in Fig. 4 provides for the 50 support and control of the movable window and this operating unit is "trimmed" with the door section enclosing the lower portion thereof. From another point of view in the illustrated construction wherein hinges 55 are installed solely on the lower door section (although my invention is obviously not limited to such a construction) it might be said that this lower door section serves as a support and suspension receiving the 60 complete window supporting and controlling unit illustrated in Fig. 4.

I have described in detail the particular embodiment of my invention shown in the 65 accompanying drawings, using specific descriptive words in doing so in order that

it might be readily understood and not attempting in the course of the description to indicate in a more generic way what was exemplified by the specific structure shown and described. The specific disclosure and language used in describing it are not therefore to be taken in a limiting sense and the more general principles exemplified by my invention which I claim as new and desire to secure by Letters Patent I shall express 75 in the following claims.

Claims:

1. That method of constructing doors of the type described characterized by constructing a tall window-casing frame which 80 provides means for movably supporting the window, constructing a lower door body of a size to terminate substantially at the belt line of the vehicle, said body being socketed to receive the frame, and fixedly securing 85 the frame in the door body to provide a fixed frame projecting above the door body to receive the window in raised position.

2. That method of constructing doors of the type described characterized by constructing a tall window-casing frame which provides means for movably supporting the window and attaching thereto mechanism for controlling its movement, constructing a door body of a size to terminate substantially 90 at the belt line of the vehicle, said body being socketed to receive the frame and fixedly securing the frame carrying said mechanism in the door body to provide a fixed frame projecting above the door body. 95 to receive the window in raised position.

3. That method of constructing doors of the type described comprising constructing a unit which includes a window casing and a lock bar, said unit providing means for 100 movably supporting the window, constructing as a second unit a door body of a size to terminate at the belt line of the vehicle and comprising a belt bar, a panel and pillars, the last having seats to receive the casing, and assembling the two units with the casing permanently projecting above the door body. 105

4. That method of constructing doors of the type described comprising constructing 110 a unit which includes a metallic window frame having channel jambs and an associated lock-bar, said unit providing for the independent assembly and coordination of the window positioning and controlling 115 means, constructing as a second unit a door body of a size to terminate substantially at the belt line of the vehicle and having a seat to receive said frame and assembling the units with said frame permanently projecting 120 above the door body to extend to the top of a door opening.

5. In a door structure a unitary assembly 125 providing a tall rigid window frame and including channel sides within which the 130

- window slides and an intermediate cross-piece secured to said sides, window controlling mechanism carried by said assembly, a window sliding within the channels and a lower door body of a size to terminate substantially at the belt line of the vehicle receiving a portion of the frame and fixedly supporting the same with a portion permanently projecting above said body.
10. 6. A door structure of the type having a sliding window comprising a tall metallic window frame having channel sides and a separable top cross-piece or lintel, an intermediate cross-piece secured to the frame, window controlling mechanism carried by said parts and a lower door body receiving a portion of said frame and fixedly supporting the same.
15. 7. In a door structure a tall metallic window frame having continuous side members within which the window slides, a sliding window in the frame and controlling means for the window, all said parts being connected together as a unit independent of the door body hereinafter recited, and a lower unitary door body fixedly assembled with said unit with the side members permanently projecting above the belt line of the door to receive the window in raised position and providing below the belt line a fixed berth for the window in lowered position.
20. 8. A door structure of the type having a sliding window comprising a rigid window-casing frame of such height as to provide for the sliding within the same of the window from its extreme lowered to its extreme raised position and providing also for the support of associated mechanisms and a lower door body embracing the lower portion of said frame and fixedly supporting the same with its upper portion permanently projecting above the belt line.
25. 9. A door structure of the type having a sliding window comprising a rigid window-casing frame of such height as to provide for the sliding within the same of the window from its extreme lowered to its extreme raised position and providing also for the support of associated mechanisms and a lower hinged door body receiving the lower portion of the frame and suspending the same with its upper portion permanently and fixedly projecting above the belt line.
30. 10. A door structure of the type having a sliding window in the upper portion thereof comprising a wieldy window unit including a metallic window frame of a size to extend to the top of the door opening, a lock-bar carried thereby and window controlling mechanism mounted on said parts and a door unit proper of a size to terminate substantially at the belt line of the vehicle and comprising a belt-bar and pillars formed to receive and support said frame.
35. 11. A door structure of the type having a sliding window in the upper portion thereof comprising a wieldy window unit including a metallic window frame, a lock-bar carried thereby and window controlling mechanism mounted on said parts and a door unit proper comprising a belt-bar and pillars having open-topped sockets receiving and supporting said frame.
40. 12. A door structure of the type described comprising a tall metallic window frame having channel sides of a size to extend to the top of the door opening, a lock-bar carried thereby, window controlling mechanism carried by said parts, a door unit of a size to terminate substantially at the belt line of the vehicle comprising pillars having seats for said frame and a belt-bar and sills carried by belt-bar and lock-bar respectively.
45. 13. A door structure of the type described comprising a tall metallic window frame having channel sides of a size to extend to the top of the door opening, a lock-bar carried thereby, window controlling mechanism carried by said parts, a door unit of a size to terminate substantially at the belt line of the vehicle comprising pillars having seats for said frame and a belt-bar and a displaceable sill carried by one of said bars.
50. 14. A door structure of the type described comprising a tall metallic window frame having channel sides and a separable top cross-piece or lintel providing access to the channels, a lock-bar carried thereby, window controlling mechanism carried by said parts, a door unit comprising pillars having seats for said frame and a belt-bar and a displaceable sill carried by one of said bars.
55. 15. A vehicle body comprising a lower body section provided with a socket receiving and fixedly supporting the lower portion of a relatively tall self-contained window frame mounted as a unit therein and having rigid side members permanently projecting above the said section and a window slideable on said members to be supported within the frame above said body section or below the belt line of the vehicle.
60. 16. In a door structure of the type having a sliding window, a lower door body terminating substantially at the belt line of the vehicle and in addition a window frame of relatively light construction as compared with the lower door body extending to the top of the door opening and comprising a lintel and channel sides in which the window slides, portions of said sides being fixedly mounted in said lower door body to support a portion of the frame in permanent position above the door body.
65. 17. In a door structure of the type having a sliding window a door body having a panel, a belt bar and pillars, said pillars having open-topped sockets or seats therein between the faces of the door, a frame in which the window slides seated in said sock-

- ets and fixedly supported by the door body, said frame comprising guides for the sides of the window and extending to the top of the door opening, one of said pillars terminating substantially at the belt line.
18. In a door structure of the type having a sliding window, a unit comprising a pair of channel guides in which the window may slide and a plurality of cross pieces rigidly to maintain said guides in a common plane and a lower door body terminating substantially at the belt line of the vehicle and fixedly supporting said unit with said guides permanently extending above the belt line to the top of the door opening.
19. In a vehicle of the type having a sliding window, a lower door body having pillars at the sides providing between them a berth for the window in lowered position and an upper portion above the belt line which consists of a fixedly projecting window frame of less width and thickness than the lower door body beneath the belt to lie between the edges and between the faces thereof and formed from a lintel and from uprights rising from the door pillars of markedly reduced thickness as compared with the latter and adapting themselves closely to the thickness of the window and being of such slight width fore and aft as consistent with providing a frame having guideways receiving the edges of the window in its raised position.
20. In a vehicle door structure of the type having a sliding window, a lower door body having pillars at the sides providing be-
- tween them a berth for the window in lowered position and an upper portion providing a fixedly projecting window frame above the belt line to receive the window in raised position, said frame formed with uprights rising from the pillars of the lower door body, which uprights are of markedly reduced thickness as compared with the pillars and are of slight width fore and aft whereby they are essentially only guides for the sliding window and the door as a whole is in effect a relatively bulky and strong body beneath the belt line carrying fixedly a relatively light window frame projecting in permanent position above the belt line.
21. A door for a closed vehicle and of the type having a sliding window, comprising a lower door body providing within the same a berth for the window in lowered position and an upper portion above the belt line forming a fixedly projecting window frame, into which the window slides when raised from said berth, said body comprising pillars at the sides and a connecting panel, one of said pillars terminating substantially at the belt line, the corresponding upright of said frame rising from said pillar and being of markedly less thickness than the latter to fit closely the thickness of the window and being of such slight width fore and aft as consistent with providing a frame element having a guideway receiving the edge of the window in its raised position.

In testimony whereof, I have signed my name to this specification.

WILLIAM H. EMOND.
